[57]

ABSTRACT

A wrench for gripping pipe and the like includes a housing having a chamber therein and a jaw member depending therefrom. A handle member has one portion within the chamber and an elongated portion extending outwardly through an open end of the housing opposite said jaw member. A jaw portion on said handle member extends outwardly through an elongated slot in the housing in facing relation with the jaw member and said housing and handle member are relatively movable to selectively adjust the space between the jaw member and jaw portion. Cooperating and interengaging fulcrum members on the jaw portion of the handle member and on the housing effect gripping of an object between the jaw member and the jaw portion in response to a movement of the handle member that pivots the jaw portion toward the jaw member.

WRENCH

The present invention relates to wrenches and more particularly to a wrench having a single moving part and fulcrum members to effect pivotal movement of the single moving part for gripping of an object between facing jaw members.

The principal objects of the present invention are: to provide a wrench which is easily and quickly adjusted to an object gripping position; to provide such a wrench which is operative to effect a positive grip on a pipe or the like positioned between jaws thereof; to provide such a wrench having a single movable member with a jaw portion thereon which is easily movable between an object engaging position and a disengaged position; to provide such a wrench having fulcrum members operative to effect positive gripping of an object between jaw portions of the wrench in response to movement of the handle which pivots a jaw portion thereon toward a jaw portion on a housing of the wrench; to provide such a wrench having resilient means to effect and maintain inter-engagement of the fulcrum members; and to provide such a wrench which is economical to manufacture, durable in construction, and particularly well adapted for the proposed use.

Other objects and advantages of this invention will become apparent from the following description taken in connection with the accompanying drawings wherein are set forth by way of illustration and example certain embodiments of this invention.

The drawings constitute a part of this specification and include an exemplary embodiment illustrating various objects and features of the wrench of the present invention.

FIG. 1 is a perspective view of a wrench embodying features of the present invention and showing jaw members thereof in gripping engagement with a pipe.

FIG. 2 is a side elevational view of the wrench with the jaw members shown in a disengaged position and portions broken away to better illustrate the component parts thereof.

FIG. 3 is a top plan view of the wrench with portions broken away.

FIG. 4 is a bottom plan view of the wrench.

FIG. 5 is an end elevational view of the wrench.

FIG. 6 is a transverse sectional view taken on Line 6-6, FIG. 2.

FIG. 7 is a transverse sectional view taken on Line 7-7, FIG. 4.

FIG. 8 is a transverse sectional view taken on Line 8-8, FIG. 4.

Referring more in detail to the drawings:

As required, detailed embodiments of the present invention are disclosed herein, however, it is to be understood that the disclosed embodiments are merely exemplary of the invention which may be embodied in various forms. Therefore, specific structural and functional details disclosed herein are not to be interpreted as limiting but merely as a basis for the claims and as a representative basis for teaching one skilled in the art to variously employ the present invention in virtually any appropriate detailed structure.

In the disclosed embodiment of the present invention, the reference numeral 1 generally designates a wrench for gripping an object, such as a pipe 2. The wrench 1 generally includes a housing member 3 and a handle member 4 having respective jaws 5 and 6 that are relatively movable to adjust the spacing and to grip

an object between the jaws 5 and 6 in response to movement of the handle member 4 pivoting the jaw 6 toward the jaw 5 of the housing member 3.

The housing 3 may be any suitable shape, however, in the structure illustrated, the housing 3 has an elongated portion 7 with spaced side walls 8 and 9 and an upper or top wall 10 and a lower or bottom wall 11 defining an elongated chamber 12 that opens outwardly at one end 13 of the housing 3. The chamber 12 has a closed end 14 spaced from the end 13 of the housing 3 and providing a thick wall 15 for strength as the jaw 5 extends therefrom in depending relation to the lower or bottom wall 11. The jaw member 5 has a face 16 inclined or at an acute angle to the bottom wall 11 and said jaw has teeth or serrations 17 thereon inclined toward said bottom wall 11 whereby the jaw 5 is a fixed or outer jaw of the wrench. The housing 3 has an elongated slot 18 in the bottom wall 11 extending from the jaw face 16 and terminating at 19 in spaced relation to the open end 13 of the housing 3. The bottom wall 11 extends toward the open end 13 from the slot 18 and is then inclined upwardly whereby an opening 20 to the chamber 12 is of reduced height. Ratchet members 21 and 22 are fixed to the housing at each side of a portion of the slot 18 and have a plurality of longitudinally spaced depending teeth or abutments, said ratchet members being mounted in a manner and for a purpose as later described.

In the illustrated structure, the ratchet members 21 and 22 are secured to the side walls 8 and 9 respectively of the housing 3 by a plurality of longitudinally spaced screws 23 extending upwardly through the ratchet members 21 and 22 and into the side walls 8 and 9. The ratchet members 21 and 22 preferably have a width greater than the thickness of the respective side walls 8 and 9 and the ratchet members 21 and 22 have respective exterior edges thereof positioned flush or in registry with exterior surfaces of the side walls 8 and 9 whereby the ratchet members 21 and 22 have facing portions extending inwardly of the side walls 8 and 9 to define a slot 24 between the ratchet members that is less in width than the elongated slot 18 which communicates with the chamber 12. It is preferred to recess the portions of the ratchet members 21 and 22 into lower portions of the walls 8 and 9. The recesses 25 are defined by surfaces 26 on the walls 8 and 9 and inclined end surfaces 27 which are engaged by the top surface 28 to the respective ratchet member and by inclined ends 29 respectively providing a dove tail mounting of the ratchet members on the housing member 3.

The handle member 4 has a first portion 30 extending into the chamber 12 and movable therein and a second portion 31 extending through the opening 20 in the end 13 of the housing 3 and extending therefrom to be gripped by person using the wrench 1. The handle member 4 has a stem portion 32 extending from the first portion 30 and through the slot 24 between the ratchet members 21 and 22. The jaw 6 is mounted on the stem portion 32 and is positioned in facing relation with the jaw 5 on the housing 3 whereby the jaw 6 is a movable or inner jaw of the wrench.

The jaw 6 has a face 33 inclined relative to the handle member 4 so as to be substantially parallel with the face 16 of the jaw 5 when the jaws 5 and 6 are in the engaged position. The face 33 of the jaw 6 has teeth or serrations 34 thereon inclined away from the bottom wall 11 thereby the teeth or serrations 17 and 34 are

inclined in substantially opposite directions when the jaws 5 and 6 engage opposite sides of an object therebetween.

The jaw 6 on the stem portion 32 of the handle member 4 has an abutment member 35 which is selectively engageable with the ratchet members 21 and 22. The abutment member 35 is mounted on the heel of the jaw 6 or spaced from the face 33 and has a plurality of upwardly extending teeth or abutments 36 engageable with the depending teeth or abutments 37 of the ratchet members 21 and 22 to provide a fulcrum whereby movement of the handle member 4 to pivot the jaw 6 toward the jaw 5 effects gripping of an object between the jaws 5 and 6. The abutment member 35 is preferably a hard long wearing material and, therefore, a separate piece secured to a rear edge portion of the jaw 6 by weld, such as brazing or by screws or other fastening means.

Resilient means are provided within the housing 3 which act on the handle member 4 to urge the abutment member 35 into engagement with the ratchet members 21 and 22. In the illustrated structure, a first or lower resilient member 38 acts between the handle member and the ratchet members and a second or upper resilient member 39 acts between the handle member and the upper wall of the housing. These resilient members may be mounted in any suitable manner as in slots or recesses, however, in the structure illustrated the lower resilient member 38 is mounted on a lower surface of the handle member 4 and is engageable with the upper edges of the ratchet members 21 and 22 and acts on the handle member 4 substantially at a point above the abutment member 35. The second of upper resilient member 39 is mounted on an upper surface of the handle member 4 and is engageable with an interior surface 40 of the upper or top wall 10 of the housing 3 and acts on the handle member 4 at a point spaced from the first resilient member 38 toward the open end 13 of the housing whereby the first and second resilient members 38 and 39 act as a couple cooperating to urge the abutment member 35 into engagement with the ratchet members 21 and 22 on the housing 3 and to urge the jaw 6 toward the jaw 5. The resilient members 38 and 39 are illustrated as leaf springs suitably secured to respective surfaces of the handle member 4, as by a plurality of screws 41 and 42 respectively.

Assembly of the wrench 1 is accomplished by moving the second portion 31 of the handle member 4 through the elongated slot 18 between the side walls 8 and 9 and into the housing member 3 and outwardly through the opening 20 in the end 13 of the housing. As best seen in FIGS. 4 to 8 inclusive, the jaw 6 extends the full width of the housing member 3, therefore, the ratchet members 21 and 22 are secured to the side walls 8 and 9 after the handle member 4 is in position within the housing 3. The resilient members 38 and 39 are movable within the housing 3 and between facing interior surfaces of the side walls 8 and 9, therefore, the resilient members 38 and 39 may be secured to the handle member 4 before or after the handle member 4 is positioned within the housing 3, however, it is preferred that the lower resilient member 38 be secured to the handle member 4 after the ratchet members 21 and 22 are secured to the side walls 8 and 9.

In using a wrench constructed as illustrated and described, the jaw member 5 on the housing 3 is posi-

tioned in engagement with one side of an object to be gripped, such as a pipe 2, and the housing 3 is held in position and the outwardly extending portion 31 of the handle member 4 is moved toward the upper or top wall 10 thereby compressing the lower resilient member 38 and moving the teeth on the abutment member 35 out of engagement with the teeth on the ratchet members 21 and 22 thereby permitting the jaw 6 and the stem portion 32 of the handle member 4 to be moved toward the face 16 of the jaw 5 until the teeth or serrations 34 on the face 33 of the jaw 6 engage the object to be gripped. The teeth or serrations 17 and 34 engage respective opposite sides or surfaces of the pipe 2 thereby gripping same between the jaws 5 and 6. When the jaws 5 and 6 are in engagement with the pipe 2 or other object, force on the handle is lessened and resilient member 38 moves the handle member 4 and jaw 6 upwardly to effect inter-engagement between the teeth of the abutment member 35 and the ratchet members 21 and 22, then movement of the outward portion 31 of the handle member 4 toward the bottom or lower wall 11 effects gripping of and turning of the pipe 2. The ratchet members 21 and 22 and the abutment member 35 cooperate to define a fulcrum for the jaw 6 on the handle member 4 to permit same to be pivoted toward and away from the jaw 5.

It is to be understood that while I have illustrated and described one form of my invention, it is not to be limited to the specific form or arrangement of parts herein described and shown.

What I claim and desire to secure by Letters Patent is:

1. A wrench comprising:
  - a. a housing having wall portions defining a chamber therein;
  - b. a jaw member on said housing and extending therefrom;
  - c. an elongated handle member having a portion extending into said chamber and movable therein;
  - d. a jaw on said handle member and positioned in facing relation with said jaw member on said housing, said handle member being movable longitudinally of said housing to move said jaw toward and away from said jaw member;
  - e. means on said jaw engageable with said housing to provide a fulcrum whereby movement of said handle member to pivot said jaw toward said jaw member on said housing effects gripping of an object between said jaw member and said jaw;
  - f. said housing has an elongated slot in one of the wall portions defining said chamber; and
  - g. said handle member has a portion extending through said slot and said jaw is mounted thereon.
2. A wrench as set forth in claim 1 wherein:
  - a. said housing has longitudinally spaced abutment members thereon; and
  - b. said jaw has an abutment member thereon selectively engageable with the abutment members on said housing to provide the fulcrum to pivot said jaw toward and away from said jaw member on said housing to vary the spacing therebetween.
3. A wrench as set forth in claim 1 wherein:
  - a. said housing has a pair of spaced ratchet members mounted thereon;
  - b. said ratchet members are positioned substantially parallel with said elongated slot and with one of

- said ratchet members on each of the opposite sides thereof;
- c. said ratchet members each have a plurality of longitudinally spaced abutment members thereon; and
- d. said jaw has an abutment member mounted thereon and selectively engageable with the abutment members on said ratchet members to provide the fulcrum to pivot said jaw toward and away from said jaw member on said housing to vary the spacing therebetween.
4. A wrench as set forth in claim 2 including resilient means in said housing and acting on said handle member to urge said abutment member on said jaw into engagement with said abutment members on said housing.

10
15
5. A wrench comprising:

- a. a housing having wall portions defining a chamber therein;
- b. ratchet members on said housing and positioned to define an elongated slot communicating with said chamber;
- c. a jaw member on said housing and extending therefrom, said jaw member being adjacent one end of said slot;
- d. an elongated handle member having a portion extending into said chamber and movable therein and a portion extending through said slot between said ratchet members;
- e. a jaw on said portion of said handle member extending through said slot between said ratchet members, said jaw being in facing relation with said jaw member on said housing and movable toward and away from same;
- f. fulcrum means on said jaw engageable with said ratchet members on said housing to provide a fulcrum whereby movement of said handle member to pivot said jaw toward said jaw member on said housing effects gripping of an object between said jaw member and said jaw;
- g. resilient means in said housing and acting on said handle member to urge said fulcrum means on said

jaw into engagement with said ratchet members on said housing.

6. A wrench as set forth in claim 5 including:

- a. first resilient means in said housing and acting on said handle member at a point above said fulcrum means on said jaw; and
- b. second resilient means in said housing and acting on said handle member at a point spaced from said first resilient means and adjacent an other end of said slot whereby said first and second resilient means cooperate to urge said fulcrum means on said movable jaw into engagement with said ratchet members on said housing and to urge said jaw toward said jaw member on said housing.

7. A wrench as set forth in claim 5 wherein:

- a. said ratchet members each have a plurality of spaced abutment members thereon; and
- b. said fulcrum means on said jaw has an abutment member thereon and selectively engageable with the abutment members on said ratchet members to provide the fulcrum to pivot said jaw toward and away from said jaw member on said housing to vary the spacing therebetween.

8. A wrench as set forth in claim 5 wherein:

- a. said housing has opposed side walls and an upper wall and a lower wall defining said chamber;
- b. said housing has an end wall closing one end of said chamber and having said jaw member extending therefrom;
- c. said jaw member is positioned to have a rearwardly facing surface thereof forming an acute angle with said lower wall;
- d. said jaw has a forwardly facing surface positioned in opposed relation with said rearwardly facing surface of said jaw member; and
- e. said rearwardly facing surface of said jaw member on said housing and said forwardly facing surface of said jaw each have a plurality of spaced serrations thereon.
